UNITED STATES PATENT OFFICE.

WHITNEY MERRILL, OF BROOKLYN, NEW YORK, ASSIGNOR TO MERRILL BROTHERS, INC., OF MASPETH, NEW YORK, A CORPORATION OF NEW YORK.

DROP-HAMMER.

1,277,985.

Specification of Letters Patent. Patented Sept. 3, 1918.

Application filed March 28, 1917. Serial No. 158,062.

To all whom it may concern:

Be it known that I, WHITNEY MERRILL, a citizen of the United States, and resident of the borough of Brooklyn, in the city 5 and State of New York, have invented a new and useful Improvement in Drop-Hammers, of which the following is a specification.

This invention relates to an improvement 10 in drop hammers, and more particularly to means for adjusting the guides or uprights which serve to direct the movement of the hammer, with the object in view of providing such an arrangement which is simple in 15 construction, very durable and positive in action, easy to operate, and accessible.

Another object consists in providing certain improvements in the form, construction and arrangement of the parts whereby the 20 above named and further objects may be effectively attained.

A practical embodiment of my invention is represented in the accompanying drawings in which,

25 Figure 1 represents a fragmentary side view showing the anvil, hammer, and guides.

Fig. 2 represents a fragmentary end view of the parts shown in Fig. 1.

Fig. 3 represents a fragmentary side view, 30 partly broken away to show the arrangement of the adjusting mechanism in the anvil and one of the guides.

Fig. 4 represents a section taken in the plane of the line IV—IV of Fig. 1, looking 35 in the direction of the arrows.

Fig. 5 represents a top plan view of the anvil and adjusting mechanism, with the guides removed.

Fig. 6 represents an enlarged detail section 40 showing one of the means for actuating the adjusting mechanism.

Fig. 7 represents an enlarged section of part of the means for actuating the adjusting mechanism, taken at right angles to the 45 section shown in Fig. 6, and

Fig. 8 represents a view similar to Fig. 7, but showing the arrangement for locking the means for actuating the adjusting mechanism.

50 In drop hammers it has been found necessary to provide a certain amount of adjustment for at least one of the guides in order to exactly register the hammer with the matrix carried by the anvil; and in order, further, to maintain exact alinement between

the guides. Various means have been tried for this purpose, but they have all been objectionable in that they were inaccessible, apt to break, lacking in durability, operative upon only one of the guides, or for 60 other reasons. My invention is calculated to overcome these defects.

Referring to the embodiment shown in the drawings, the anvil is denoted by 1, the hammer by 2, and the guides by 3, 4. Inasmuch as this invention has nothing to do with the form of lifting board or mechanism for actuating the hammer, the same is not shown.

The anvil is cut away centrally in the 70 usual dove-tail formation for receiving the matrix, and each of its upper side parts has a transversely extending groove 5, 6, which are fitted to receive tongues 7 that project downwardly from the bottoms of the guides 75 3, 4. While these tongues 7 are only shown in connection with the guide 3, (see Fig. 3), it will be understood that the other guide 4 is similarly fashioned.

The upper side parts of the anvil 1, also 80 have diagonally extending channels 8, 9, which are calculated to receive similarly shaped portions 10, 11, of the adjusting bars. The channels 8, 9, and co-operating portions 10, 11, of the adjusting bars are 85 rectangular in cross section. The said bars also comprise heavy splines 12, 13, which are formed integral with the portions 10, 11, and lie above the latter. These splines 12, 13, are fitted to have a tight sliding engagement with slots 14 cut in the bottoms of the guides 3, 4, intermediate the tongues 7. While only one slot 14 is shown, viz: that formed in the guide 3, (see Fig. 3), it is to be understood that the guide 4 is similarly 95 provided.

The portions 10, 11, of the adjusting bars are screw-threaded at one end for engagement with the nuts 15 and 16; which nuts are rotatable in circular recesses 17, and 18. 100 Each of these nuts is also provided with an annular series of sockets 19 and 20, fitted to receive a spanner or spike for rotating the nuts in a well understood manner.

In order to prevent the nuts 15 and 16 105 from moving longitudinally in the recesses 17 and 18, and to provide outer bearing shoulders for the said nuts, I arrange collars 21 and 22, which slidably engage the threaded ends of the parts 10 and 11 of the 110

adjusting bars, and which are fixed against longitudinal and rotary movement in the recesses 17 and 18, respectively, by means of cap screws 23 and 24.

5 Each of the nuts 15 and 16 also has a second annular series of sockets 25, which are fitted to receive lugs 26 carried by locking springs 27 secured to the anvil by means of cap screws 28. This arrangement serves 10 to lock the nuts against rotary movement.

In operation, when the parts are arranged and assembled as above described, it is simply necessary for the operator to lift one of the springs 27 so that its lug 26 no 15 longer engages the socket 25 in the adjacent nut, and then, by rotating the nut, the adjusting bar is caused to move longitudinally. Owing to the fact that the bars are arranged to slide in angularly disposed grooves, as

20 already mentioned, this longitudinal movement will not only slide the spline 12 or 13 in its slot 14, but it will cause the said spline 12 or 13 to move laterally with respect to the anvil, that is, longitudinally 25 with respect to either of the grooves 5 or 6. This last named movement of the spline which is being actuated, will impart movement in a similar direction to the guide 3 or 4, which it engages, and will thus cause the

30 guide to move toward or away from the center of the anvil. Both guides may be similarly adjusted. When the proper adjustment has been made, the locking devices 25, 26, 27, may be utilized for preventing

35 further movement of the adjusting bars, and the guides 3, 4, may be additionally secured in the desired adjustment by means of bolts 29, 29 and 30, 30. Slots 31, 31 and 32, 32, are provided in the anvil, through which the bolts 29, 29, and 30, 30 pass, so as to permit 40 the said bolts to move with the guides 3, 4, as the latter are adjusted.

It will be understood that various changes 45 may be resorted to in the form, construction and arrangement of the several parts without departing from the spirit and scope of my invention, and hence I do not intend to be limited to the details herein shown and described, except as they are specifically included in the claims.

50 What I claim is:

1. In a drop hammer, an anvil, a hammer 55 guide, and means for laterally adjusting the one with respect to the other, said means comprising a bar engaging the one at an acute angle to the line of adjustment and en-

gaging the other at an angle to its engagement with the one, said engagements permitting longitudinal but preventing lateral movement of the bar, and means for imparting longitudinal movement to the bar. 60

2. In a drop hammer, an anvil, a hammer guide, and means for laterally adjusting the guide with respect to the anvil, said means comprising a bar engaging the anvil at an acute angle to the line of adjustment and engaging the guide at an angle to its engagement with the anvil, said engagements permitting longitudinal but preventing lateral 70 movement of the bar, and means for imparting longitudinal movement to the bar.

3. In a drop hammer, an anvil, a hammer guide, and means for laterally adjusting the one with respect to the other, said means 75 comprising a bar engaging the one at an acute angle to the line of adjustment and engaging the other at an angle to its engagement with the one, said engagements permitting longitudinal but preventing lateral 80 movement of the bar, means for imparting longitudinal movement to the bar, and means for locking the bar against longitudinal movement.

4. In a drop hammer, an anvil, a hammer 85 guide, and means for laterally adjusting the one with respect to the other, said means comprising a groove fashioned in the one at an acute angle to the line of adjustment, a slot fashioned in the other at an angle to the 90 said groove in the one, an adjusting bar having two parts, one part fitted to slide in the said groove and the other part fitted to slide in the said slot, and means for imparting a sliding movement to the bar in the said 95 groove and slot.

5. In a drop hammer, an anvil, a hammer guide, and means for laterally adjusting the guide with respect to the anvil, said means comprising a groove fashioned in the anvil 100 at an acute angle to the line of adjustment, a slot fashioned in the guide at an angle to the groove in the anvil, an adjusting bar having two parts, one part fitted to slide in the said groove and the other part fitted 105 to slide in the said slot, and means for imparting a sliding movement to the bar in the said groove and slot.

In testimony, that I claim the foregoing as my invention, I have signed my name this 110 22 day of March, 1917.

WHITNEY MERRILL.
